UNITED STATES PATENT OFFICE.

FRANK G. KOEHLER, OF ST. LOUIS, MISSOURI.

HAND-TRUCK.

1,096,630.

Specification of Letters Patent. Patented May 12, 1914.

Application filed May 2, 1913. Serial No. 765,029.

To all whom it may concern:

Be it known that I, FRANK G. KOEHLER, a citizen of the United States of America, and a resident of the city of St. Louis, Missouri, 5 have invented certain new and useful Improvements in Hand-Trucks, of which the following is a full, clear, and exact description, reference being had to the accompanying drawings, forming part of this specification.

10 My invention relates to hand trucks of the type illustrated by Letters Patents issued to me January 9, 1912, and July 23, 1912, numbered respectively, 1,014,400 and 1,033,- 15 421. Hand trucks of this type include metal frames and wooden handles attached to the frames, and the practice in making such trucks has included attaching the handles to the truck frames by bolts extending 20 through the handles and the frames. A serious objection to this practice is found in the fact that the production of the bolt holes through the wooden handles weakens the latter very materially so that the handles will not withstand the strains imposed 25 thereon. Furthermore, when the wooden handles as heretofore made were broken it was necessary to replace them with new wooden handles similar to those previously 30 in use, and much trouble has been encountered in the renewal owing to difficulties in obtaining proper registration of the bolt holes in the handles and the bolt holes in the truck frame owing to difference of 35 shrinkage of wood used for the production of the handles.

40 My present invention has for its object to provide a simple and efficient construction whereby wooden handles may be applied to the metal frames of hand trucks without the extension of bolts through the handles to connect them to the truck frames, whereby the troubles mentioned are obviated.

45 Figure I is a perspective view of part of the frame of the truck and a handle secured thereto in accordance with my present invention. Fig. II is an inverted plan view of one of the handles. Fig. III is an enlarged cross section taken on line III—III, 50 Fig. I. Fig. IV is an enlarged cross section taken on line IV—IV, Fig. I.

55 In the accompanying drawings I have shown only the rear portion of the frame of my truck at one side of the truck, and

the handle fitted to this portion, it being understood that the frame is of similar structure at its opposite side and a handle similar to that shown is utilized at that side.

1 designates the metal side bar of the truck frame and 2 is the rear cross bar secured to said bar and also to the opposite side bar. The cross bar 2 is of angle shape in cross section, comprising a horizontal flange, and a vertical flange extending 60 downwardly at the front of the horizontal flange. The vertical flange of the cross bar is of such length as to fit between the side bars of the truck frame and it is provided at its ends with forwardly extending strap 70 members 3 which are secured by rivets or other suitable means to said side bars. The horizontal flange of the cross bar 2 has straps extensions 4 which extend over the side bars 1, then downwardly along the 75 outer faces of the side bars, and then inwardly to form arms 5 which lie beneath the frame side bars and parallel with the horizontal flange of the cross bar. The extensions of the cross bar are secured to the 80 frame side bars by suitable means, such as rivets 4' that extend through the vertical portions of said extensions and through the side bars 1 of the truck frame.

6 designates one of a pair of U-shaped 85 clips, the base members of which are fitted to the outside faces of the truck side bars 1, to which they are secured by rivets 6' or other suitable means, and the spaced horizontal arms of which straddle and extend 90 inwardly from said side bars.

7 designates one of the wooden handles secured to the side bars of the truck frame by arranging it in the clip 6 and between the horizontal flange of the cross bar 2 and the arm 5 beneath said horizontal flange, suitable means to be hereinafter described being furnished to hold the handle between said members. This handle abuts at its forward end against the rear face of the vertical flange of the truck frame cross bar 2, and is provided at its bottom adjacent its forward end with a stop device which serves to prevent rearward movement of the handle by engagement with the lower arm 5 carried by the cross bar 2. The device shown in the drawings for this purpose comprises a plate 8 secured by a screw 9, (see Fig. II), or other suitable means, to the handle, the plate being provided at its for- 100 105 110

ward end with a down-turned lip 10, which engages the forward edge of the cross bar arm 5.

11 and 12 are bolts that extend, respectively, vertically through the horizontal flange and arm 5 of the cross bar 2, and through the arms of the clip 6. These bolts serve to draw the members they are arranged in toward each other, whereby the handle is securely clamped between said members and, the bolts being arranged in said parts, parallel with the truck frame side bar 1 and in close proximity to the side of the handle opposite that presented against the truck side frame bar, serve to hold the handle against said frame bar. To provide for the handle being more securely held within the clip 6, one or both of the arms of said clip may be provided with a spur 6' formed by upsetting the metal of the clip, as illustrated most clearly in Fig. IV.

I claim:

1. A hand truck, comprising a side frame member, a bar secured to and extending transversely relative to said side frame member, a clip carried by said side frame member, and a handle secured in said clip and abutting against said bar; said handle being provided with means in engagement with said bar whereby rearward movement of the handle is prevented.

2. A hand truck, comprising a side frame member, a bar secured to said side frame member and extending transversely relative thereto, the said bar including top and bottom members parallel with each other and a vertical flange, a clip carried by said side frame member located back of said transverse bar, and a handle arranged in said clip and between the top and bottom members of said transverse bar, the said handle abutting at its forward end against the vertical flange of said transverse bar, and being provided with means for engagement with said transverse bar whereby rearward movement of the handle is prevented.

3. A hand truck, comprising a side frame member, a bar secured to said side frame member and extending transversely relative

thereto, the said bar including top and bottom members parallel with each other, a U-shaped clip carried by said side frame member located back of said transverse bar, and a handle arranged in said clip and between the top and bottom members of said transverse bar, the said handle abutting at its forward end against said transverse bar and being provided with means for engagement with said transverse bar whereby rearward movement of the handle is prevented. 60

4. A hand truck, comprising a side frame member, a transverse bar secured to said side frame member, the said transverse bar comprising a horizontal top flange and a vertical flange extending downwardly from the forward edge of the top flange, the said transverse bar being provided with a strap extension secured to said side frame member and terminating in a horizontal flange 70 beneath the horizontal flange of said bar, a clip carried by said side frame member located back of said transverse bar, a handle, and means in said transverse bar and said clip whereby said handle is removably secured to said members. 75

5. A hand truck, comprising a side frame member, a transverse bar secured to said side frame member, the said transverse bar comprising a horizontal top flange and a vertical flange extending downwardly from the forward edge of the top flange, the said transverse bar being provided with a strap extension secured to said side frame member and terminating in a horizontal flange 80 beneath the horizontal flange of said bar, a clip carried by said side frame member located back of said transverse bar, a handle, a bolt extending through the horizontal flange and horizontal arm of said transverse 90 bar adjacent to the side of said handle opposite that facing said side frame member, and a bolt extending through the arms of said clip adjacent to the side of said handle opposite to that facing the side frame member. 95

FRANK G. KOEHLER.
